(57) **CLAIM**

The ornamental design for a handled container, as shown and described.

DESCRIPTION

FIG. 1 is a perspective view of the first embodiment of a handled container, showing my new design;
FIG. 2 is a first side elevation view thereof;
FIG. 3 is a front elevation view thereof;
FIG. 4 is a rear elevation view thereof;
FIG. 5 is a second side elevation view thereof;
FIG. 6 is a top plan view thereof;
FIG. 7 is a bottom plan view thereof;
FIG. 8 is a perspective view of the second embodiment of a handled container, showing my new design;
FIG. 9 is a first side elevation view thereof;
FIG. 10 is a front elevation view thereof;
FIG. 11 is a rear elevation view thereof;
FIG. 12 is a second side elevation view thereof;
FIG. 13 is a top plan view thereof; and,
FIG. 14 is a bottom plan view thereof.
